CLAIM

The ornamental design for a wall plate, as shown and described.

DESCRIPTION

FIG. 1 is a perspective view of a wall plate for a switch illustrating my new design.

FIG. 2 is a front elevational view of the wall plate of FIG. 1.

FIG. 3 is a vertical elevational view of a wall plate for a wall receptacle illustrating my new design, the surface decoration being shown only in one corner segment only for ease of illustration.

FIG. 4 is a vertical elevational view of a wall plate for two side-by-side switches illustrating my new design, the surface decoration being shown only in a corner fragment as in FIG. 3.

FIG. 5 is a rear elevational view of the wall plate of FIG. 1.

FIG. 6 is a side elevational view of the wall plate as in FIG. 1.

FIG. 7 is an end plan view of the wall plate of FIG. 1.

FIG. 8 is a vertical sectional view of the wall plate of FIG. 5 taken along the lines 8—8 of FIG. 5.

FIG. 9 is a horizontal sectional view of the wall plate of FIG. 5 taken along the lines 9—9 of FIG. 5.

The undisclosed rear and sides of the second embodiment shown in FIG. 4 is substantially similar to that shown in the views of the first embodiment.
